Application April 30, 1943, Serial No. 485,244
 In Great Britain May 6, 1942

4 Claims. (Cl. 179—114)

This invention relates to electromagnetic devices provided with a magnetic structure which provides paths for polarising flux and varying flux and directs the fluxes into a vibratory armature of magnetic material. The invention may be applied to devices in which an electrical input is converted into a mechanical motion after the fashion of a vibratory motor, such as electromagnetic relays or driving units for telephone or sound reproducing instruments, or in which the device is driven mechanically and provides an electrical output, as is the case with electromagnetic pick-ups for gramophones or vibratory magneto-electric generators.

The invention is more particularly concerned with the magnetic structure for such devices by means of which the fluxes are applied to the vibratory armature.

According to the invention, the magnetic structure includes at least two magnetic circuits for carrying polarising fluxes which flow in parallel through the vibratory armature, and at least two magnetic limbs through which varying or reversal fluxes flow and which join points of substantially equal mean magnetic potential in the said two circuits carrying the polarising flux. In the simplest arrangement, there are two magnetic circuits carrying polarising flux and two carrying varying flux, and the magnetic limbs referred to carry the windings for the reversals or line currents. In such a case, there are two pairs of pole-pieces presented to the armature surfaces, each pair lying in one of the magnetic circuits carrying the varying flux, and one pole-piece of each of those pairs forms part of one of the magnetic circuits carrying the polarising flux, and the other pole-piece of each pair forms part of the other magnetic circuit carrying polarising flux. The windings carrying the reversals or line currents are connected to produce magneto-motive forces which cause fluxes to pass through the armature in opposite directions. When the fluxes tend to pass through the armature in opposite directions, the armature is urged from side to side and may be pivoted to permit such motion, or may be mounted so as to be capable of bodily movement in a straight line.

Some examples of various kinds of devices provided with magnetic circuits in accordance with the invention will now be described with reference to the accompanying drawings, in which:

Figures 1, 2 and 3 show in plan view and vertical sections on the line 2—2 and 3—3 respectively in Figure 1 a form of telephone receiver in accordance with the invention; while

Figure 4 is a central cross-section of a form of telephone receiver having an armature approximately rhombus-shaped; and

Figure 5 is a detailed perspective view of its armature.

In Figures 1 to 3, a form of telephone receiver in accordance with the invention is illustrated, but in this case the whole movement which is enclosed in a case consisting of an upper moulding 10 42 and a lower moulding 43, has four magnetic circuits for the polarising flux and four for the varying flux. There are in fact housed in the moulding four sets of upper laminations 44 and four sets of lower laminations 45. The armature 15 is a magnetic diaphragm 46, and the pole-pieces 47, of which there are eight in this case, terminate in faces parallel to the armature 46. The latter is a stamping with four outwardly-projecting lugs 48, as seen in Figure 1, which are secured 20 to insets 49 in the lower part of the moulding 43 by four screws 50. Thus the diaphragm is mounted to permit linear vibration along an axis normal to its plane. The lower half of the moulding 43 is formed with a moulded cavity 51, and the upper 25 half of the moulding 42 with an outlet 52 with its lower wall 53 perforated. The diaphragm 46 is sealed to the wall of the outlet 52 by means of a flexible ring 54. In this case, there are four upper magnets 55 and four lower magnets 56, 30 each magnet being of right-angle shape as seen in Figure 1, and they are magnetised with their like poles adjacent to one set of stampings 44 as indicated by the letters NS in Figure 1. It will be appreciated that, in this case, there are four 35 magnetic circuits in parallel for the polarising flux from the top magnets 55, and four magnetic circuits in parallel for the polarising flux for the lower magnets 56, the flux passing in the armature 46 horizontally as seen in Figure 2, from one 40 pole-piece 47 to the adjacent pole-piece 47 on either side of it.

There are four limbs formed by separate laminations and shown at 57, connecting points of substantially equal mean magnetic potential in the laminations 44 and 45. Each carries a winding 58 for the signal or line current. The four windings 58 are connected so that the fluxes at the gaps above the armature 46 are all increased at times that the flux at the gaps below the armature is decreased so that the armature is drawn as a unit upwardly and downwardly due to the signal currents.

The lower surfaces of the moulding 42 are all flush and the upper surfaces of the moulding 43 are all flush, and the laminations 47 are of such

a size that their pole-faces are flush with the surfaces of the moulding. The two halves of the mouldings 42, 43 are secured together by bolts and nuts 59, and the correct spacing of the pole-faces of the laminations 47 from the armature 48 is obtained by the insertion of a spacing ring 60 between the two mouldings 42, 43, and of a thickness equal to the thickness of the armature 48 together with the air gaps desired above and below the armature.

In Figures 4 and 5, a form of telephone receiver is shown in which the magnetic structure is very similar to that used in Figures 1 to 3 but employing only four pole-pieces and using a different shape of armature. The armature 14 is of a lozenge-shape or in the form of a rhombus with the angles at the top and bottom relatively obtuse and with the points at the corners of the rhombus omitted, and provided with projecting rods 61, from each of its obtuse corners. These rods 61 are formed by having a central plate 62 of the same shape as the laminations of the armature 14 but substantially thicker and intended to reinforce the armature, the laminations of which are riveted on either side of the plate 62. The plate 62 is stamped with opposite projections corresponding to the pins 61 and these projections are swaged up from the flat to form the circular pins 61. The pin 61 at the bottom is secured by nuts to a flat spring 63, and the pin 61 at the top is secured by nuts to the diaphragm 64 which is clamped around its edge. Thus armature 14 is mounted for linear vibration along an axis parallel with the rod 61 passing through the narrow dimension of the armature. The magnets in this case are annular permanent magnets 65 which are magnetised so as to present opposite poles at opposite ends of a diameter as indicated by the letters NS in Figure 4. A magnetic limb 6 connects pole-piece 10 with pole-piece 12 and carries a winding 8, and a similar magnetic limb connects pole-piece 11 with pole-piece 13 and carries a winding 9. The whole assembly is housed in a moulded casing 66 with a screw-on cover and earpiece 67. The windings 8, 9 are connected so as to produce magneto-motive forces tending to cause fluxes to pass through the armature in opposite directions, that is to say, if the varying flux passing from the pole-piece 10 to 12 at any instant is downwards, that passing between the pole-pieces 11 and 13 at that instant is upwards. Consequently, if the flux at the pole-piece 10 is increased, so is the flux at the pole-piece 11, while at the same instant the flux at the pole-pieces 12 and 13 is decreased. Therefore, the armature 14 is moved up and down bodily to provide a balanced linear movement which is imparted to the diaphragm 64.

We claim:

1. An electromagnetic device comprising, in combination, a magnetic armature mounted for linear vibration along a given axis, a pair of magnetic pole-pieces arranged on one side of said armature and forming two air gaps with respect to said armature, a second pair of pole-pieces arranged on the opposite side of said armature and forming two air gaps with respect to said armature, said pole-pieces being positioned so that movement of said armature along said axis increases the gaps of one pair of pole-pieces and simultaneously decreases the gaps of the second pair, and vice versa, polarizing means for establishing a polarizing flux in one portion of said armature through said first pair of pole-pieces,

and polarizing means for establishing a polarizing flux in another portion of said armature through said second pair of pole-pieces, a pair of magnetic paths connecting the pole-pieces on one side of said armature with the pole-pieces on the opposite side of said armature, and a pair of windings surrounding said magnetic paths and producing magneto-motive forces tending to cause fluxes in the gaps of one pair of pole-pieces to be increased and the fluxes in the gaps of other pair of pole-pieces to be simultaneously decreased.

2. An electromagnetic device for the interconversion of electrical and mechanical vibrations comprising, in combination, a magnetic armature mounted for linear vibration along a given axis, a magnetic structure including polarizing means for establishing a polarizing flux in a portion of said armature and transversely of said axis, a second magnetic structure including polarizing means for establishing a polarizing flux in another portion of said armature on the opposite side of said armature from said first portion and transversely of said axis, a pair of magnetic limbs each connecting two points in said magnetic structures, said points being at substantially the same mean magnetic potential derived from said polarizing means, and a winding surrounding each of said magnetic limbs, said windings being mutually connected to produce magneto-motive forces tending to cause the flux on one side of said armature to be increased at times when the flux on the other side of said armature is decreased.

3. An electromagnetic device comprising, in combination, a diaphragm of magnetic material constituting an armature, means for mounting said diaphragm for linear vibration along an axis normal to the plane of the diaphragm, a magnetic structure including a pair of spaced pole-pieces presenting polar faces to one side of said diaphragm and including polarizing means for establishing a polarizing flux in said diaphragm between said pole-pieces, a second magnetic structure including a pair of pole-pieces presenting polar faces to the opposite side of said diaphragm and including polarizing means for establishing a polarizing flux in said diaphragm between said pole-pieces, a pair of magnetic limbs each connecting two points in said magnetic structures, said points being at substantially the same mean magnetic potential derived from said polarizing means, and a winding surrounding each of said magnetic limbs, said windings being mutually connected so that one of said windings tends to produce a magnetic flux transversely of the plane of said diaphragm between two pole-pieces located on opposite sides of said diaphragm, and the other winding tends to produce a magnetic flux transversely of the plane of said diaphragm between two poles on opposite sides of said diaphragm but in an opposite direction from said first transverse flux.

4. An electromagnetic device, comprising, in combination, a magnetic armature having the shape of a rhombus, means for mounting said armature for linear vibration along the short axis thereof, four magnetic pole-pieces presenting polar faces to the four faces of said rhombus, polarizing means for two of said pole-pieces positioned on opposite sides of said axis for establishing a polarizing flux through a portion of said armature transversely of said axis, second polarizing means for the remaining two of said pole pieces on opposite sides of said axis for estab-

lishing a polarizing flux in said armature parallel with said first polarizing flux and in the same direction, a magnetic limb joining the two pole-pieces on one side of said axis and a second magnetic limb joining the two pole-pieces on the opposite side of said axis, and a winding carried by each of said magnetic limbs, one of said windings

tending to establish a flux in said armature parallel with said axis, and the other winding tending to establish a flux in said armature parallel with said axis but in a direction opposite to the flux established by said first winding.
